UNITED STATES PATENT OFFICE

EDWARD FRANCIS MILLER, OF MANLY, SYDNEY, NEW SOUTH WALES, AUSTRALIA

AUDIO AMPLIFICATION VALVE

Application filed August 6, 1928. Serial No. 297,889.

The invention is principally for employment in connection with a valve of ordinary type used in receiving from a wireless aerial or in connection with a microphone, the object being to amplify the effect induced in such a valve by impulses from an aerial or from a microphone or from a similar existing medium.

Impulses from the medium affecting said valve of ordinary type are more readily amplified and a larger number of stages of amplification can be obtained, than hitherto has been generally possible.

When one of my valves, or a number of them in series, is, or, are employed in connection with said valve of ordinary type, the audio frequency transformer usually used is dispensed with.

My valve is comprised of an evacuated bulb, a filament, two soft iron grids each encased in insulating material, two plates coupled by a common lead, and a "horseshoe" electromagnet.

The filament is located between the grids, and the plates are arranged one outside of each grid and parallel thereto, the poles of the electromagnet are connected by a magnetic conductor one to each of the grids.

Electronic emission from the filament tending to affect the plates is controlled by the magnetic field set up between the grids, the magnetic field being produced and controlled by the electromagnet which is excited by current from a secondary battery.

The winding of the electro magnet is electrically connected at one end to the two plates and at the other end to the plate of the valve of ordinary type referred to, or when in a series, to both plates of the preceding valve according to this invention.

One of the filament leads is common to the negative poles of a primary and of the secondary battery.

My invention is illustrated in the accompanying drawing wherein:—

Fig. 1 is a front elevation and

Fig. 2, a plan,

Fig. 3 is a diagrammatic illustration of the employment of a series of valves.

50 Referring first to Figs. 1 and 2:

The evacuated glass bulb 1. contains the filament 2. which is electrically connected to the adapter pin 3. and 4.

The soft iron grids 5. and 6. preferably encased in glass or other insulating material are severally connected by the magnetic conductors 6' and 7. to the respective poles 8. and 9. of a horseshoe electromagnet 10. which is excited by current in the winding 11. one end of which is connected to terminal 12. 60 while the opposite end is connected to the two plates 13. and 14. disposed one upon each side of the grids and parallel therewith.

The electromagnet is supported by the arms 15. A lead 16. connects the plates to a 65 terminal 17.

Referring now to Fig. 3:

The parts corresponding to those referred to in the description of Figs. 1 and 2 are indicated by the same reference numerals. 70

The diagram illustrates the disposition and connection of a series of valves.

The first valve 18. is of the ordinary three electrode type having the filament 19. grid 75 20 and plate 21.

The conductor 22. from the negative pole of a primary battery is also connected by lead 23. to the negative pole of the secondary battery.

The return conductor 24. is connected to the filament 19. of valve 18., and also to the filament 2. of each of the other valves in the series.

Under working conditions current from the secondary battery passes from filament 19. 85 to plate 21. which is connected through the windings of the series of electromagnets 10. to the positive pole of the secondary battery.

The electromagnets are thereby excited and as opposing poles thereof are connected 90 to the respective grids a magnetic field is produced which magnetizes individually each electron given off from the filament which are attracted towards the grid.

The electrons near the grid are more influenced by the plate than by the grid and are attracted by the positive pull of the plate thereby causing a flow of current from the secondary battery to the plate.

95 The current from valve 18. plus the current 100

induced by the next valve passes to the electro-magnet of the next succeeding valve wherein the amplification is repeated and so on throughout the series whereby the current finally available for use is the sum of the current induced by all the valves.

A variation of potential in the grid 20. of valve 18. causes a variation in the amount of current from the secondary battery passing from the filament to the plates in each of the 10 succeeding valves in the series.

I claim:

1. An audio amplification valve wherein are combined a filament, two grids and two 15 plates parallel with the grids, a horse-shoe electromagnet, magnetic connection between the poles of the magnet and each of said grids, the magnet being surrounded by a winding one end of which is connected to the plates and 20 the other to a terminal on the valve.

2. In an audio amplification valve a filament, a horseshoe electromagnet, two soft iron grids, magnetic connecting means between the poles of the magnet and the grids, 25 the winding of the magnet connected at one end to a terminal on the valve and the opposite end designed for electrical connection to the plate of another valve.

In testimony whereof I have signed my 30 name to this specification.

E. F. MILLER.
